UNITED STATES PATENT OFFICE.

THOMAS W. ARTER, OF BELLAIRE, OHIO.

DESIGN FOR A TYPEWRITER MAT.

61,287.

Specification for Design.

Patented Aug. 1, 1922.

Application filed November 23, 1920. Serial No. 426,092. Term of patent 14 years.

To all whom it may concern:

Be it known that I, THOMAS W. ARTER, a citizen of the United States, residing at Bellaire, in the county of Belmont and State of Ohio, have invented a new, original, and ornamental Design for a Typewriter Mat, of which the following is a specification, reference being had to the accompanying drawings, forming a part thereof.

The figure is a plan view of the typewriter mat showing my new design.

I claim:

The ornamental design for a typewriter mat as shown.

THOMAS W. ARTER.
